[57] CLAIM

The ornamental design for a fishhook extractor, as shown and described.

DESCRIPTION

FIG. 1 is a side elevational view of a fishhook extractor showing our new design;

FIG. 2 is a top view thereof;

FIG. 3 is a bottom view thereof;

FIG. 4 is a rear view thereof; and

FIG. 5 is a front view thereof.

The other side is a mirror image of the side shown in FIG. 1.
